UNITED STATES PATENT OFFICE

155,573

DESIGN FOR A RUBBER BOOT

George H. Bingham, Jr., Taneytown, Md., assignor to The Cambridge Rubber Company, Taneytown, Md., a corporation of Maryland

Application February 6, 1948, Serial No. 144,330

Term of patent 14 years

(Cl. D7—4)

To all whom it may concern:

Be it known that I, George H. Bingham, Jr., a citizen of the United States, residing at Taneytown, Carroll County, State of Maryland, have invented a new, original, and ornamental Design for a Rubber Boot, of which the following is a specification, reference being had to the accompanying drawing forming a part thereof.

In the accompanying drawing,

Figure 1 is a perspective view of a rubber boot, showing my new design with the top turned up; and

Figure 2 is a similar view of the same boot with the top turned down.

The dominant features of the design reside in

the top portions of the rubber boot as illustrated in both figures.

I claim:

The ornamental design for a rubber boot, substantially as shown and described.

GEORGE H. BINGHAM, JR.
